MECHANICAL TUNER FOR CAVITY RESONATORS

Filed April 4, 1945

UNITED STATES PATENT OFFICE

2,542,908

MECHANICAL TUNER FOR CAVITY
RESONATORSPalmer P. Derby, Boston, Mass., assignor to Ray-
theon Manufacturing Company, Newton, Mass.,
a corporation of Delaware

Application April 4, 1945, Serial No. 586,610

3 Claims. (Cl. 315—5)

1

My present invention relates to electron-discharge devices, and more particularly to tunable electron-discharge devices of the so-called magnetron type.

The main object of my present invention is to provide means for effecting a mechanical linkage, in a device of the general character indicated, between tuning means located within said device, and tuning control means located exteriorly of said device.

This, and other objects of my present invention, which will become more apparent as the detailed description thereof progresses, are attained, briefly, in the following manner:

As above indicated, my present invention is especially suitable for use with an electron-discharge device of the magnetron type. I prefer that said device include an anode structure, made of highly conductive material, such as copper, and comprising a cylindrical body provided with a plurality of interiorly-extending, radially-disposed anode members, each adjacent pair of said anode members, together with that portion of said cylindrical body lying therebetween, constituting a resonant line.

I prefer to provide said anode structure with at least one pair of conducting straps alternately contacting successive anode members, the straps of each pair being so disposed with respect to each other as to present a capacitance therebetween, said capacitance, together with the capacitance and inductance built into the device as a function of the geometry thereof, determining the natural resonant frequency at which the device normally operates.

I further prefer to provide the device with another conducting member, which is adapted to be introduced into the space between the straps of at least one of the above-mentioned pairs thereof, the introduction of this conducting member so altering the above referred to inter-strap capacitance, and adding such other capacitance, as to thereby enable the tuning of the device to a frequency other than its natural resonant frequency.

In order to control the movement of the last above-referred to conducting member from the exterior of the device, it is necessary to provide some mechanical linkage between the interiorly-located tuning means and the exteriorly-located control means, and for this purpose, I prefer to hollow at least one of the magnetic pole pieces associated with the device for establishing an appropriate magnetic field therein, and pass said mechanical linkage through said hollowed pole piece.

In the accompanying specification I shall describe, and in the annexed drawing show, an illustrative embodiment of the electron-discharge devices of my present invention. It is,

however, to be clearly understood that I do not wish to be limited to the details herein shown and described for purposes of illustration only, inasmuch as changes therein may be made without the exercise of invention, and within the true spirit and scope of the claims hereto appended.

In said drawing, the single figure is a longitudinal sectional view taken substantially through the center of a tunable magnetron made in accordance with the principles of my present invention.

Referring now more in detail to the aforesaid illustrative embodiment of my present invention, and with particular reference to the drawing showing the same, the numeral 5 generally designates an electron-discharge device of the so-called magnetron type. Said device comprises an anode structure 6, a cathode structure 7, magnetic means 8 for establishing a magnetic field in a direction perpendicular to the path of the electron-flow between said cathode and anode structures, and tuning means 9.

In the device shown, the anode structure 6 includes a cylindrical body 10 made of highly conductive material, such as copper, said body being provided with a multiplicity of radially-disposed, interiorly-extending anode members in the form of vanes 11, each adjacent pair of said vanes, together with that portion of said cylindrical body lying therebetween, constituting a resonant line whose natural resonant frequency is, as is well known in the art to which my present invention relates, a function of the geometry of the physical elements making up the same. I shall further describe the anode members 11 when referring, in a later portion of this specification, to the details of the tuning means 9.

The anode structure is closed at its ends, for example, by end plates 12 and 13, with the junctions between the cylindrical body 10 of said structure, and said plates 12 and 13, hermetically sealed, as at 14.

The cathode structure 7, which is coaxial with the anode structure 6, includes a cathode sleeve 15, conventionally made of nickel, or the like, provided with a reduced portion 16 whose length, preferably, is coextensive with the width of the anode members 11, said reduced portion 16 being provided with a highly electron-emissive coating 17, for example, of the well-known alkaline-earth metal oxide type.

In order properly to support the cathode sleeve 15 with respect to the anode members 11, said sleeve may be reduced, as at 18, to fit into an elongated, electrically-conductive tubular member 19 having, at its outer end, a ferrule 20 closed by a glass seal 21. Said seal, together with one or more glass beads 22 disposed within the tubular member 19, supports a lead-in conductor 23 which passes through said member 19 and has

its upper end connected, as at 24, to one terminal of a cathode heating filament 25. The other terminal of said filament may be connected, as at 26, to the cathode sleeve 15.

In order to convey current to the filament 25, the lead-in conductor 23 is connected by a conductor 27 to one terminal of a suitable source of electromotive force (not shown), the other terminal of said source of electromotive force being connected by a conductor 28 to a heat-dissipating member 29 fixed upon the lower end of the tubular member 19.

In order properly to support the cathode structure 7, and insulate the same from the anode structure 6, the tubular member 19 may have fixed thereto a cup-like bushing 30 sealed into one end of a glass tube 31, the other end of said glass tube having sealed therein a tubular bushing 32, in turn, secured to a tubular pole piece 33, constituting one of the components of the magnetic means 8.

Said pole piece 33 may be hermetically sealed, as at 34, into the end plate 12, and be provided with a central bore 35 whereby the cathode structure 7 may enter the device.

Another tubular pole piece 36 may be hermetically sealed, as at 37, into the end plate 13, said pole piece and the pole piece 33 being fixed, for example, to the opposite ends of a horseshoe magnet (not shown), whereby an appropriate magnetic field may be established, as previously indicated, in a direction perpendicular to the path of the electron-flow between the cathode structure 7 and anode structure 6.

Now, by suitably heating the cathode, and applying a proper potential difference between said cathode and the anode, the device can be made to generate electrical oscillations of a wave length determined, primarily, by the capacitance and inductance built into said device as a function of the geometry thereof, and more especially, of the dimensions of the above referred to resonant lines defined by the anode structure.

In order to extract power from the device I may, for example, introduce a loop 39 between the anode members 11 defining one of said resonant lines, said loop coupling with the magnetic component of the above-mentioned electrical oscillations. Said loop may, in turn, be connected to a conductor 40 supported in a glass seal 41 fused into an outlet pipe 42, said pipe being threaded and hermetically sealed into the cylindrical body 10 of the anode structure 6.

In the device as thus far described, there is no external control over the frequency of the generated oscillations and, furthermore, because of the numerous paths which the oscillating energy can follow within the anode structure of said device, spurious oscillations are present which reduce the efficiency of the device.

In order to eliminate these disadvantages, I proceed as follows:

Each anode member 11 is provided, preferably, in both its upper and lower edges, adjacent its inner end, with cut-away portions or slots 43, said slots being receptive of two pairs of concentric conducting straps 44 and 45, and 46 and 47, the straps of each pair thereof alternately contacting successive anode members 11. Said straps present therebetween capacitances entering into the determination of the natural resonant frequency of the device.

It has been found that when alternate anode members are electrically inter-connected as just described by the straps 44 to 47, inclusive, the

spurious oscillations above referred to become suppressed.

It has also been found that inasmuch as the straps of each pair thereof have a capacitance therebetween, they may be considered the plates of a capacitor, and by varying said capacitance, and introducing additional capacitance in parallel therewith, the device can be tuned, and this may be accomplished as follows:

10 A plunger 48, made of highly conductive material, such as copper, is slidably mounted in the bore 49 of the tubular pole piece 36, the inner end of said plunger being recessed, as at 50, to accommodate the upper end of the cathode structure 6, and the extremity thereof being cupped to provide a conducting annulus 51, which, when moved, for example, intermediate the straps 44 and 45, constitutes, together with said straps, a variable capacitor.

15 In order to maintain the device air-tight, I provide an apertured flexible diaphragm 52, hermetically sealed, at its periphery 53, to the cylindrical body 10 of the anode structure 6, and similarly sealed, at its central aperture 54, to said plunger 48.

20 25 The introduction of the annulus 51 into the space between the straps 44 and 45 does two things. First, it reduces the effective area of the surfaces of said straps between which the above-mentioned capacitance exists, but inasmuch as this capacitance is small to begin with, the overall effect on the frequency of the device is, likewise, small. Second, it forms, together with said straps, two capacitors, connected in series, which did not, before, exist. Inasmuch

30 35 as the gaps between said annulus and said straps are small, the total capacitance of the newly formed capacitors is relatively large, and this capacitance, added in parallel with what remains of the original capacitance, has a considerable effect upon the frequency of the device.

40 There remains to be described the control mechanism of the tuning means 9, by means of which the penetration of the annulus 51 into the space intermediate the straps 44 and 45 may be varied.

45 50 While not limited thereto, I prefer to construct such tuning control means as follows:

Secured on the upper end of the plunger 48 is a threaded bushing 55, engageable in a disk 56 whose periphery may be provided with a V-cut 57, constituting a ball-bearing race. Surrounding said race is another race comprised of two cooperating bevelled rings 58 and 59, the ring 58 being carried by a disk 60, and the ring 59 being pressed into cooperation with said ring 58 by an annular spring 61. The races are receptive therebetween of bearing balls 62, and the spring 61 is affixed to the disk 60 by a flat retaining ring 63 and bolts 64.

60 65 The disk 60 is maintained against rotation by being bolted, as at 65, to a plate 66 fixed, at its center, to the pole piece 36, the plate 66 being provided with bearings (not shown) in which is journaled a shaft 67. Mounted upon the shaft

65 70 75 is a worm gear 69 engageable with a worm wheel 70 secured to the disk 56 by means of bolts 71. The shaft 67 is provided, at one end, with a pinion 72, whereby the same may be manually or otherwise rotated, slidably to move the plunger 48 with respect to the pole piece 36, and thus vary the capacitances between the straps 44 and 45, and the annulus 51 and said straps.

This completes the description of the aforesaid illustrative embodiment of my present invention. It will be noted from all of the foregoing that I

have provided, in a tunable magnetron, simple means for effecting mechanical linkage between the tuning means located within the magnetron, and the control means therefor, located outside of said magnetron. Other advantages of my present invention will readily occur to those skilled in the art to which the same relates.

What is claimed is:

1. An electron discharge device comprising a hollow body defining a portion of an enclosing vessel, an anode and a cathode within said vessel, said anode having portions defining a cavity resonator, conductive members connected, respectively, to points of opposite polarity on said cavity resonator, a mounting member joined to said body, a guide supported by said mounting member, a driving member slidably fitted within said guide for motion toward and away from said anode, a carrier mounted by said driving member, a tuning member supported by said carrier and extending intermediate said conductive members, means including a flexible bellows forming a hermetic seal between said carrier and said enclosing vessel, and means coupled to said driving member for actuating it to displace said carrier and said tuning member, thereby to tune said cavity resonator.

2. A tunable electron discharge device comprising: an anode structure incorporating a cavity resonator; a pair of conductors connected, respectively, to points of opposite polarity on said cavity resonator; a pole piece carried by said anode

5 structure and provided with a bore; a plunger mounted for reciprocation in said bore; a third conductor disposed intermediate said pair of conductors; and means extending from said plunger and supporting said third conductor.

10 3. An electric discharge device of the magnetron type comprising a generally cylindrical envelope, a resonant anode structure supported within said envelope, a cathode supported from one end of said envelope and a tuning mechanism supported from the other end of said envelope, said cathode and said tuning mechanism being carried, respectively, by magnetic pole pieces which extend through opposite ends of said envelope from the exterior to the interior thereof.
